United States Patent Office

Des. 203,913

Patented Feb. 22, 1966

203,913

ASH TRAY OR THE LIKE

Walter I. Bieger, Minneapolis, Minn., assignor to Arthur Salm Inc., Chicago, Ill., a corporation of Illinois

Filed Mar. 15, 1965, Ser. No. 84,256

Term of patent 14 years

(Cl. D85—2)

FIG. 1 is a prespective view of an ash tray showing my new design;

FIG. 2 is a top plan view thereof;

FIG. 3 is a cross-sectional view taken on the line 3—3 of FIG. 2; and

FIG. 4 is a side elevational view thereof.

I claim:

The ornamental design for an ash tray or the like, substantially as shown.
